INNER TUBE TESTER

Walter A. Bishman, Osseo, Minn.

Application October 5, 1946, Serial No. 701,469

3 Claims. (Cl. 73—49)

1

This invention relates to a device for testing inner tubes such as are customarily used in pneumatic tires of various types of vehicles.

It is an object of the invention to provide a tester which will hold the tube in a generally upright position, i. e. the position which it assumes in a tire on a wheel, wherein the tube can be placed on the tester and a portion of the apparatus lowered to submerge at least a portion of the tube in a pan of water such as is generally found in an ordinary automobile tire service station; and further to permit rotation of a portion of the support and the tube in order that successive sections of the tube can be submerged during the inspection operation.

Another object of the invention is to provide an inner tube tester which completely supports the tube in an upright position and wherein the tube supporting portion thereof can be releasably held in a lowered position to keep the lower portion of the tube submerged without pressure on the part of the operator, and the tube supporting portion of the tester can also be moved to an elevated position with the tube out of the water and maintained therein without being supported by the operator.

Still another object of the invention is to provide a tube tester of the type described above which is adaptable for use with a conventional tire service station water pan which is usually of relatively narrow elongated proportions and wherein the tube supporting structure is or can be closely associated with a water pan in such a way as to take up as little space as possible.

The above and other objects and advantages of the invention will more fully appear from the following description made in connection with the accompanying drawings, wherein like reference characters refer to the same parts throughout the views, and, in which:

Figure 1 is a front elevational view of the device showing a tube thereon with a water pan in longitudinal vertical section and the tube holding unit in its lowered position in full lines and in its elevated position in dotted lines;

Figure 2 is a transverse vertical sectional view taken approximately on the line 2—2 of Figure 1;

Figure 3 is an enlarged fragmentary side elevational view of the tube support pivotal mounting and stop structure;

Figure 4 is a rear elevational view of the structure shown in Figure 3; and

Figure 5 is an enlarged fragmentary sectional view taken approximately on the line 5—5 of Figure 2.

2

The supporting frame of the apparatus includes a pair of upwardly converging rods 6 having bent-over lower ends 7 serving as bases or feet. As indicated in Figures 1 and 2 the bases 7 of the rods 6 may be placed over a conventional tube testing water pan 8 such as is found in most tire service stations, and if desired the feet 7 may be secured to the bottom of the pan 8 in any suitable manner such as by welding if the pan and tester are sold as a complete unit.

The upper ends of the upwardly converging rods 6 are bent rearwardly or to the right as viewed in Figures 2 and 3, and as indicated at 9. The upper bent ends 9 of the rods 6 are spaced slightly apart as shown in Figure 4 and are welded to the under side of the bridge portion 10 of an inverted U-shaped bracket 11. As best shown in Figure 4, the right hand or rear leg of the bracket 11 is cut off at two of its corners 12 and 13.

Extending through the legs 14 and 15 of the bracket 11 and pivoted relative thereto is the upper horizontal portion 16 of a crank 17 which serves as a tube support mounting. The crank 17 has a vertical intermediate portion 18 and an outwardly extending relatively long horizontal portion 19. A plurality of radial arms 20 extend from a bearing 21 on the crank portion 19 and the bearing 21 and arms 20 are rotatable on said crank portion 19 as a unit, the radial arms 20 being welded to the bearing, as best shown in Figure 5. As illustrated in Figure 1, there are six arms provided although the number is not critical.

Extending horizontally outwardly from each of the arms 20 is a rod 22 and each of the rods 22 is bent inwardly slightly toward the horizontal rotational axis of the radial arm unit 20 as indicated at 23. It will be seen that the parallel rods 22 which extend outwardly from the radial rods or arms 20 lie at spaced points about a circle whose central axis is the axis of rotation of the bearing 21 about the horizontal elongated crank portion 19.

On the other horizontal crank portion 16 which is pivotally mounted in the bracket 11 is an L-shaped stop member 24 which is fixed on the crank portion 16 to pivot therewith. As best illustrated in Figure 4, the horizontal portion 24a of the stop member 24 will clear the upper and lower cut away corners 12 and 13 on the rear leg 15 of the bracket 11. However, the horizontal stop portion 24a will strike the upper right hand portion of the bracket 11 as indi-

cated by the dotted line showing in Figure 4, and it will permit swinging of the crank and the stop member counterclockwise, as viewed in Figure 4, until the horizontal stop portion 24a strikes the lower right hand corner of the bracket 5

In operation the crank 17 is swung to its upper limit of movement which would be the dotted line position in Figure 1 and the stop 24 will be in the dotted line position of Figure 4. The tube 25 is then slipped on the horizontally disposed parallel rods 22, the inwardly bent ends 23 facilitating the insertion of a tube thereon, it being contemplated that the circle described by the parallel portions of the horizontal rods 22 be of such diameter as to cause the rods 22 to frictionally engage the tube 25 and hold the tube rather securely thereon. The outer portions of the radial arms 20 serve as a backing against which the tube is pressed and thereby facilitating proper positioning of the tube on the horizontal rods 22 which with the radial arms 20 constitute the tube support per se. The crank arm 19 is then grasped and swung in a clockwise direction, as viewed in Figure 1, whereupon the tube support will swing downwardly with the crank portion 19 to immerse the lower portion of the tube in the water in the tank 3, as illustrated in the full line position of Figure 1 and also shown in Figure 2. The crank is swung until the horizontal stop portion 24a assumes the position shown in Figure 4 which is past the rotational center of the crank. The natural buoyancy of the inflated tube 25 will cause an upward pressure and in view of the fact that the stop member 24 is over center the tube and its support will be maintained in the lowered position above mentioned. The operator can inspect the tube portion which has been initially submerged and then by rotating the spider made up of the radial arms 20 and the horizontal rods 22 which extend therefrom can bring successive portions of the tube to a lowermost position beneath the surface of the water in the pan 3. Consequently, the operator does not have to press downwardly on the tube as is necessary when testing is done entirely by hand, and he can

devote his entire attention to inspection of the tube leaving both hands free to brush away bubbles which customarily accumulate when a dry inner tube is placed in the water. His inspection is, therefore, considerably facilitated and the operator has the use of both hands as well as his eyes in making his inspection.

It will, of course, be understood that various changes may be made in the form, details, arrangement and proportions of the various parts without departing from the scope of my invention.

What I claim is:

1. In an inner tube tester for use in conjunction with a water pan, a supporting standard, a shaft 15 pivotally carried by said standard above the lower portion thereof and having a crank portion extending outwardly therefrom to overlie the water pan, a tube engaging and supporting unit rotatably supported on said crank portion and means 20 for selectively retaining said crank portion in raised and lowered position above and below the axis of said shaft.

2. The structure set forth in claim 1, said means comprising upper and lower stops carried 25 by said standard and in the path of swinging movement of said crank portion.

3. The structure set forth in claim 1, said means comprising upper and lower stops in the path of swinging movement of said crank portion, 30 said stops being located at one side of a vertical plane taken through the axis of said shaft and said crank portion having freedom for swinging movement between one stop and the other stop, through slightly more than 180 degrees.

35 WALTER A. BISHMAN.
